OTHER PUBLICATIONS

Copy of drawings of a planter banding hood illustrated in U.S. Design Patent Application No. 327,558, filed Mar. 23, 1989, now abandoned, which banding hood was in public use and on sale more than one year prior to the filing date of the subject application.

Primary Examiner—Lisa P. Lichtenstein
Attorney, Agent, or Firm—William L. Huebsch

[57] CLAIM

The ornamental design for a spray hood, as shown and described.

DESCRIPTION

FIG. 1 is a top, front, right end isometric view of a spray hood showing our new design;

FIG. 2 is a top plan view of said spray hood;

FIG. 3 is a front elevational view of said spray hood;

FIG. 4 is a rear elevational view of said spray hood;

FIG. 5 is a right end elevational view of said spray hood; and,

FIG. 6 is a left end elevational view of said spray hood. The bottom view of said spray hood is essentially the inverse of the top plan view shown in FIG. 2.
